UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR IN SHUTTLE FOR LOOMS.

Application filed July 26, 1926. Serial No. 124,899.

This invention relates to weft detectors for looms and it is the principal object of the invention to provide a detector very sensitive in its operation and exerting a minimum of 5 pressure on the yarn, the operating part which communicates indication of weft exhaustion to the loom preferably being out of contact with the yarn at all times.

It has been found that when fine yarns 10 such as rayon are used in automatic looms that a bobbin will run for such a length of time that the usual form of detector will abrade the weft to such a degree that a mark will be left in the cloth when that part of 15 the filling which has been subjected to the repeated blows of the detector is being incorporated in the fabric. It is an important object of my present invention to provide a detector so arranged that the part corresponding to the ordinary weft detector will 20 be kept out of contact with the yarn or weft by means of a gate which normally closes a slot in the shuttle, said gate being movable at the time of substantial exhaustion of weft 25 to give an indicating movement to a loom controller.

It is a further object of the invention to provide a detector in a shuttle having a very light weft engaging member which controls 30 the position of a gate for an aperture in the shuttle so that when sufficient weft is present the gate will cover the aperture and be operatively related with respect to a stop, the stop taking the thrust of the controller, but 35 when insufficient weft is present the member will be raised past a substantially empty bobbin to move the gate away from the stop to permit free movement thereof when engaged by the controller, such free movement 40 resulting in indication of weft exhaustion to effect a change in the operation of the loom.

With these and other objects in view which will appear as the description proceeds, my invention resides in the combination and arrangement of parts hereinafter described 45 and set forth in the claims.

In the accompanying drawings wherein I have shown a convenient embodiment of my invention,

50 Fig. 1 is a top plan view of a lay end and loom controller together with a shuttle provided with my present invention,

Fig. 2 is a vertical section on an enlarged scale on line 2—2 of Fig. 1 looking toward

the shuttle and showing the gate in locked 55 position corresponding to a sufficient supply of weft,

Fig. 3 is a view similar to Fig. 2 but with the gate moved to unlocked position, a condition corresponding to an insufficient supply 60 of weft,

Fig. 4 is a vertical section on line 4—4 of Fig. 2,

Fig. 5 is a vertical section on line 5—5 of Fig. 3,

Fig. 6 is an enlarged view of a portion of Fig. 4 showing in greater detail the construction of the shuttle carried gate in the position the same assumes when a sufficient supply of weft is present,

Fig. 7 is a view similar to Fig. 6 but with the parts in indicating position when insufficient yarn is present, and

Fig. 8 is a detail plan view of the yarn engaging part of the device, showing the 75 bristles disposed at an angle.

Referring to the drawings it will be seen that I have provided a lay 10 having a box back 11 and a shuttle S in which is located a bobbin B. Said lay is provided with a binder 12 acted on by the usual binder spring (not shown) to check the shuttle as the same enters the box and hold the same against the box back 11. A stand 13 secured to fixed structure such as the loomside (not shown) 80 is provided with a pair of spaced guides 14 through which extends the right hand arm of a controller 15. A collar 16 secured to the controller receives the rearward thrust of a compression spring 17 the forward end of 85 which pushes against one of the guides 14. Said controller extends to the left as at 18 in front of a portion 19 of the transerrer arm and then extends rearwardly as at 20 through front and back guides 21 and 22, 90 respectively.

A block 23 is suitably guided by structure not shown to have a reciprocating movement in a vertical direction, moving downwardly 100 on each detecting beat of the loom so as to cause a corresponding motion on the part of an actuator lever 24 pivoted as at 25 on the block. A connector 26 the lower end of 105 which is shown in Fig. 1 is attached to the left hand end of the lever 24 while the right hand end of the latter extends through a vertical slot 27 in the bearing 22. Said bearing is provided with a bore 28 extend-

ing across the slot 27. When sufficient weft is present the arm 15 of the controller, which is normally under the actuator lever 24, will be moved forwardly so that the left hand portion 20 will be moved from under the actuator lever 24, permitting the latter to move downwardly without interruption. When insufficient weft is present, however, the member 15 will not be moved forwardly but will be held in rearward position by the spring 17 so that downward motion of the lever 24 is interrupted. The motion of block 23 is therefore communicated to the connector 26 and a corresponding indication of weft exhaustion will be given to the magazine in a manner similar to that set forth in Patent No. 1,080,748.

In carrying out my improvements I provide the front wall 40 of the shuttle S with a slot 41 occupying substantially the same position as the corresponding slots in the usual self-threading shuttle used in automatic looms and I secure to the inner part of the wall 40 a bracket 42 extending above and below the slot 41 and having on the lower portion thereof a stop tongue 43 which may be located intermediate the ends thereof as indicated in Fig. 3. Each side of the bracket has stamped therefrom a tongue 44 terminating in a stop or guide 45.

A pin 46 extends across the upper part of the slot 41 and has the ends thereof held in the bracket 42. A weft detector 47 is pivoted on said pin by having the latter passed through the end ears 48 of said detector member. Bristles 49, as indicated in Fig. 8, are glued in holes drilled in said detector and they are preferably disposed oblique to the axis of the bobbin.

A closure or gate 50 formed of a piece of flat stock has ears 51 bent therefrom to provide bearings by means of which the gate or closure is pivotally mounted on a small rod 52 extending between opposite sides of the detector 47. A coil spring 53 surrounds the rod 52 and has one end extending downwardly against the lower body portion of the gate 50 and has the other end extended as at 54 in contact with the detector 47. The effect of said torsion spring is to exert a pressure on the detector tending to move the same from the position indicated in Fig. 6 to that shown in Fig. 7.

Under normal conditions when there is a sufficient supply of weft in the shuttle as indicated in Figs. 4 and 6 the gate 50 will be held in front of the stop tongue 43 because of the fact that the yarn on the bobbin engages the bristles 49 to hold the detector 47 in down position against the action of spring 53. The guides 45 prevent motion of the gate 50 to the right under action of said torsion spring.

On each detecting beat of the loom the lay will tend to move forwardly and the clo-

sure 50 will engage the arm 15 of the controller and move the same yieldingly forward against the action of spring 17, the thrust of spring 17 pushing the gate against the stop tongue 43 without exerting an appreciable increase in the pressure of the bristles against the yarn. As weaving continues the diameter of the weft on the bobbin becomes smaller and the angular position of the detector 47 changes, assuming more nearly a horizontal position. When the diameter of the weft has reached a predetermined minimum amount the bristles 49 will move upwardly to the position indicated in Figs. 5 and 7, the length of the bristles determining the amount of weft to remain on the bobbin at the time of indication.

The upward movement of the bristles and detector 47 will move the gate 50 to a raised position above the stop tongue 43 by reason of the fact that the connection of said closure with the detector is eccentric with respect to the axis of said detector. On the next detecting beat of the loom, therefore, the controller will engage the gate 50 but as the latter is not braced by the stop 43 the controller will move the gate inwardly toward the bobbin away from the guides 45 and against the action of spring 53 to some such a position as is indicated in Fig. 7. The controller end 20 therefore remains under the actuator lever 24 and an indication of weft exhaustion is given to the loom to effect a change in the operation thereof as previously described.

On transferring beats of the loom the portion 19 of the transerrer arm will be moved forwardly away from the bobbin, the effect of which will be to remove the end 15 of the controller to the right of the position shown in Fig. 7, thus permitting spring 53 to move the gate 50 to the forward position against the stops 45 as indicated in Fig. 5. The under surface of the incoming full bobbin will engage the bristles 49 and move the same downwardly to the position indicated in Fig. 4, this downward movement carrying the lower end of the closure 50 in front of the stop tongue 43 so that the device is effectively reset, being placed in resetting position by the spring 53. It is to be understood that the yarn is so wound on the bobbin as to move downwardly on that side of the bobbin adjacent the bristles.

From the foregoing it will be seen that I have provided a very simple device for keeping the relatively heavy controller 15 out of contact with the weft of the bobbin, the only part of the detector which engages the filling being the bristles 49 and their pressure being no greater than that which is exerted by spring 53. Furthermore, it will be seen that the device is very easily reset merely by moving the controller forwardly in a manner similar to that which exists in devices

at present in use. Also, the bristles, being disposed at an angle and pointing in the same direction as the yarn moves toward the shuttle eye, offer a minimum of resistance 5 to the yarn. Furthermore, should the yarn balloon into the spaces between the bristles, it will be able to move out along the inclined surfaces more easily than would be the case should the bristles be perpendicular rather 10 than oblique relatively to the axis of the bobbin.

Having thus described my invention it will be apparent that changes and modifications may be made therein by those skilled 15 in the art without departing from the spirit and scope of the invention, and I do not wish to be limited to the details herein disclosed, but what I claim is:

1. In a weft detector for a loom having 20 an actuator to effect a change in the operation of the loom and a controller for the actuator normally operatively positioned with respect to said actuator, and a shuttle having an opening therethrough, a closure 25 for the opening movable relatively to the shuttle, a stop secured to the shuttle and normally positioned to engage a portion of the closure to prevent movement of the closure toward the weft supply in the shuttle, and means dependent upon the amount 30 of weft in the shuttle to control the position of the closure relatively to the stop, said controller being rendered inoperative relatively to the actuator by the closure when 35 sufficient weft for continued weaving is present and said closure being movable out of operative relationship with the stop and toward the weft supply when insufficient weft is present to render the controller oper- 40 ative with respect to the actuator to cause the latter to effect a change in the operation of the loom.

2. In a weft detector for a loom having an actuator to effect a change in the operation 45 of the loom and a controller for the actuator normally operatively positioned with respect to said actuator, and a shuttle having an opening therethrough, a closure to engage the controller movably mounted on the shuttle and normally positioned to close the opening, a stop fixed to the shuttle and normally preventing movement of the closure when 50 the latter is in contact with the controller and sufficient weft is present, said controller 55 being yieldable to move out of position with respect to the actuator, and means in contact with the weft in the shuttle and dependent upon the amount of weft present to move the closure relatively to the stop, 60 said means acting when insufficient weft is present to move the closure away from the stop, whereby the latter is ineffective to move 65 the controller and the latter remains operatively positioned with respect to the actuator.

3. In a weft detector for a loom having an actuator to effect a change in the operation of the loom and a controller for the actuator normally operatively positioned with respect to said actuator, and a shuttle having an opening therethrough, a closure movably mounted with respect to the shuttle and normally positioned to move the controller out of operative position with respect to the actuator when sufficient weft is present, a 70 weft engaging element connected to the closure and controlling the position of the latter, and stop means mounted on the shuttle, said closure normally being in position to be engaged by the stop and the element 75 being effective when insufficient weft is present to move the closure out of relationship with respect to the stop means, whereupon the closure will be ineffective to move the controller relatively to the actuator. 80

4. In a weft detector for a loom having an actuator to effect a change in the operation of the loom and a controller for the actuator normally operatively positioned with respect to said actuator, and a shuttle having an opening therethrough, a closure 90 for the opening to engage the controller and movably mounted with respect to the shuttle, stop means normally operatively placed with respect to the closure and holding the 95 latter against motion under influence of the controller so as to cause the latter to move out of position relatively to the actuator on non-indicating detecting beats of the loom, an element having weft engaging bristles to move past the center of the body of weft, resilient means connected to the closure and element, said bristles when insufficient weft is present moving beyond the center of the weft to cause the resilient means to move 100 the closure out of position with respect to the stop, whereupon said closure will be ineffective to move the controller relatively to the actuator. 105

5. In a weft detector for a loom having an actuator to effect a change in the operation of the loom and a controller for the actuator normally operatively positioned with respect to said actuator, and a shuttle having an opening therethrough, a closure for the 110 opening to engage the controller and movably mounted with respect to the shuttle, stop means normally operatively placed with respect to the closure and holding the latter against motion under influence of the controller so as to cause the latter to move out of position relatively to the actuator on non-indicating detecting beats of the loom, an element having weft engaging bristles to move past the center of the body of weft, 115 resilient means connected to the closure and element, said bristles when insufficient weft is present moving beyond the center of the weft to cause the resilient means to move the closure out of position with respect to the 120 actuator. 125

6. In a weft detector for a loom having an actuator to effect a change in the operation of the loom and a controller for the actuator normally operatively positioned with respect to said actuator, and a shuttle having an opening therethrough, a closure for the opening to engage the controller and movably mounted with respect to the shuttle, stop means normally operatively placed with respect to the closure and holding the latter against motion under influence of the controller so as to cause the latter to move out of position relatively to the actuator on non-indicating detecting beats of the loom, an element having weft engaging bristles to move past the center of the body of weft, resilient means connected to the closure and element, said bristles when insufficient weft is present moving beyond the center of the weft to cause the resilient means to move the closure out of position with respect to the actuator. 130

stop, whereupon said closure will be ineffective to move the controller relatively to the actuator, said bristles being disposed obliquely with respect to the surface to be detected.

6. In a weft detector for a loom having an actuator to effect a change in the operation of the loom and a controller for the actuator normally operatively positioned with respect to said actuator, and a shuttle having an opening therethrough, a closure on the shuttle to determine the position of the controller on detecting beats of the loom, and a weft engaging element to control the position of the closure, said element having a plurality of bristles disposed obliquely with respect to the weft in the shuttle and extending in the direction in which the weft is paid off during the weaving process.

7. In a weft detector for a loom having an actuator to effect a change in the operation of the loom and a controller for the actuator

normally operatively positioned with respect to said actuator, and a shuttle having an opening therethrough, a closure movably mounted on the shuttle and normally positioned to engage the controller and move the latter relatively to the actuator on detecting beats when sufficient weft is present, a weft engaging element mounted on and movable with respect to the closure, a stop on the shuttle for the closure, and resilient means interposed between the closure and the element and tending to hold the element against the weft and the closure in a position intermediate the stop and the controller, whereby when the closure is moved from an inoperative to an operative position with respect to a stop on transferring beats of the loom said closure will be properly positioned with respect to the stop.

In testimony whereof I have hereunto affixed my signature.

ELBRIDGE R. HOLMES.
